UNITED STATES PATENT OFFICE.

ROBERT M. DIXON, OF EAST ORANGE, NEW JERSEY, ASSIGNOR TO
SAFETY CAR HEATING & LIGHTING COMPANY, A CORPORATION
OF NEW JERSEY.

HOSE-COUPING.

SPECIFICATION forming part of Letters Patent No. 760,856, dated May 24, 1904.

Application filed May 18, 1903. Serial No. 157,573. (No model.)

To all whom it may concern:

Be it known that I, ROBERT M. DIXON, a citizen of the United States, residing at East Orange, Essex county, State of New Jersey, have 5 invented certain new and useful Improvements in Hose-Couplings, of which the following is a specification.

My invention relates to hose-couplings, and has for its object to produce a hose-coupling 10 which may be readily coupled and uncoupled.

In the accompanying drawings I have shown a coupling in which one form of my invention is embodied.

In the drawings, Figure I is a plan view of 15 the coupling. Fig. II is a side elevation; and Fig. III is an end elevation, of the coupling looking from right to left in Fig. I.

In the drawings, *a* represents the coupler-head, herein shown as provided with a straight 20 port *b* and with a gasket *c* seated therein. A ribbed side arm or bracket *d* is provided at the side of the coupler-head, carrying an undercut lug or engagement member *e*. This lug or engagement member *e* is adapted to engage 25 with another undercut lug or engagement member *f* at the side of the body of a corresponding coupler-head.

In order to provide means whereby the coupler-heads may be readily engaged one 30 with the other, I have provided a fulcrum-lug *g*. This lug is shown in the present instance as having a curved or inclined face and as located at the lower edge *h* of the coupler-head on the side next the side arm *d* and integral 35 with the said coupler-head. This lug *g* is shown as extending less than half of the width of the coupler-head, and the arm *d* is shown as of greater depth than the height of the coupler-head, by which I mean the rectangular- 40 faced portion shown in Fig. III.

It will be obvious that when the couplings are put together in the usual manner the lower edge *h* of each coupler-head will rest upon the curved or beveled face *i* of the lugs 45 *g*; so that the lug will not only form a bearing or fulcrum for the swinging movement of the coupler-head, but by reason of its curved

or inclined face *i* will serve to guide the coupler-heads into their ultimate positions.

It will be observed that the face *i* of the 50 lug *g* is shown convexly curved throughout its entire extent, there being no concave portion thereof whatever. In Fig. II it is shown as curved from front to rear, and in Fig. III it is shown as laterally curved from the lateral edge *g*.

I am aware that it has been proposed to form a coupler with a rib extending substantially half the width of the coupling with a recess extending the remaining half of the 60 width of the coupling, such as is shown in patent to Beery, No. 494,816, March 28, 1893, and I do not herein claim such a construction. The construction which I have described, which I shall hereinafter claim, constitutes 65 not only a fulcrum for the swinging movement made when the parts are coupled together, but also constitutes a guide for bringing the parts together with certainty and in this sense, among others, is distinguishable 70 from the construction herein disclaimed.

Having described my invention, what I claim, and desire to secure by Letters Patent, is—

1. The combination of a coupler-head having a side arm *d* provided with a lug or engaging means *e* and a lug or engagement means *f* on the coupler-head and a combined fulcrum bearing and guiding lug *g* having an inclined face located at the lower edge of the 80 coupler-head *a*.

2. The combination of a coupler-head and side arm provided with reciprocal locking means of a guiding and fulcrum lug *g* having an inclined face and adapted to serve both as 85 a guide for guiding the coupler-head into its coupled position and as a fulcrum for the coupler-heads, the said lug being located at one side of the median line of the coupler-head.

3. The combination of a coupler-head, means 90 for securing the same to a complementally-formed coupler-head, and a side lug *g* located at the lower edge of the coupler-head, the said lug *g* having an inclined face adapted to serve

as a guiding and bearing surface for the lower edge of a complementally - formed coupler-head.

4. The combination in an integral construction of a coupler-head *a*, a side arm or bracket *d* and a lug *g* serving to guide the coupler-head into its coupled position, the said lug *g* being integral with the coupler-head *a* and the side arm *d* and located at the junction of the coupler and side arm.

5. The combination in an integral construction of a coupler-head *a*, a side arm or bracket *d* and a lug *g*, the said lug *g* being integral with the coupler-head *a* and the side arm *d* at the junction of the coupler-head and side

arm, the said side arm extending below the said coupler-head and the said lug forming a lateral prolongation of the said side arm.

6. The combination of a coupler-head and a side arm each having complemental coupling means, of a combined guiding and fulcrum lug at the operating-face of the coupler-head, the said lug serving to guide the coupler-heads together when coupling same and also serving as a fulcrum. 20

R. M. DIXON.
